UNITED STATES PATENT OFFICE.

HERMANN VON FORSTER, OF FRANKFORT-ON-THE-MAIN, GERMANY.

MACHINE FOR DRAWING THIN-WALLED METAL TUBES.

1,204,832.

Specification of Letters Patent. Patented Nov. 14, 1916.

Application filed August 18, 1915. Serial No. 46,178.

To all whom it may concern:

Be it known that I, HERMANN VON FORSTER, subject of the King of Prussia, residing at Roseggerstrasse 32, Frankfort-on-the- 5 Main, Germany, have invented certain new and useful Improvements in Machines for Drawing Thin-Walled Metal Tubes, of which the following is a specification.

My invention relates to the manufacture 10 of thin-walled metal tubes and its particular object is a machine for drawing such tubes in a cold state in a great number of succeeding passes without annealing the tubes between the passes. This mode of 15 manufacture of thin-walled tubes offers the advantage of a great economy of time, much time being lost in the old methods by the annealing operations, so that it took several days to make a tube whereas with the ma- 20 chine according to this invention a raw blank is converted into a thin-walled tube within a few minutes. To this end a great number of dies (from 20 to 30 and even more) are arranged in line at one end of 25 the machine. These dies are passed in close succession over the blank causing it to be drawn out substantially uniformly in each pass, gripping devices or the like being provided on the machine for gripping the 30 dies or the die holders and for guiding them over the blank.

In view of the rapid succession of passes required for finishing the thin tubes in the shortest possible time provision must be 35 made for a very effective lubrication, and means must be provided for neutralizing the heat locally generated in those places where the drawing tools are working. To this end the entire upper part of the ma- 40 chine is preferably constructed so as to form a trough filled with lubricant, the blank as well as the dies being immersed in the liquid lubricant altogether and a very effective equalization of temperature all over the 45 blank being obtained besides the lubrication.

Each metal allowing to be drawn out but at a certain temperature, and each lubricant presenting the greatest lubricating power at 50 a certain temperature also, the machine according to this invention is further provided with means, preferably arranged below the trough containing the lubricant, for heating or cooling and for imparting to the blank, the dies and the lubricant the temperature most suitable for the drawing procedure.

Preferably the composition of the lubricant should be such as to present the highest possible lubricating power at the temperature which is the most favorable for drawing the 60 respective metal. The trough may be replaced by other suitable devices such as spraying or rinsing devices for distributing the lubricant.

In the drawings accompanying this 65 specification the preferred form of a machine according to my invention is represented, Figure 1 being a vertical longitudinal section, Fig. 2 a detail, in section, Fig. 3 a plan view.

a are standards carrying the trough *b* enclosing the drawing mechanism.

c is a heating device arranged below the trough.

d is a heating tube for passing a hot 75 liquid or steam through the trough.

e is the mandrel rigidly fixed to the trough at one end by a nut *f* while the other end lies loosely on a support *g*.

h is the hollow blank placed on the mandrel. The fixed end of the mandrel which is reduced in thickness as usual is of such diameter as to allow the smallest die required in the drawing operation to be drawn over it. The dies *i* are placed in a line upon the reduced end of the mandrel within the trough. A gliding piece *k* carrying grippers *l* is movably arranged within the trough and is linked to the ends of connecting rods *m* fastened, at their other ends, to a gliding piece *r* movable on guides outside the trough. A pair of slotted oscillating levers *p* linked to a horizontal pivot below said gliding piece *r* embrace a bolt *o* fastened to the connecting rods *m* near the gliding 85 piece. 90 95

q is a crank disk rotated by suitable means and connected with said oscillating levers.

The operation of this machine is as follows: After the hollow blank *h* and all the 100 dies *i* have been placed upon the mandrel, the foremost die is brought in contact with and seized by the grippers *e* pulling it, under the action of crank *q*, levers *p* and connecting rods *m*, over the blank and releasing 105 it at the end of the mandrel. The grippers and the gliding piece *k* carrying them are then returned automatically to the starting place and the next die is gripped and pulled over the blank, and this drawing 110 operation is repeated until all the dies have passed over the blank. The trough is filled.

with a lubricant, such as for instance a soap solution to which water-soluble oils have been added. The composition of the lubricant can be made such that it will have a good lubricating effect even at temperatures between 100 and 200 degr. C. The temperature is controlled by aid of the heating or cooling devices provided for this end.

While the temperatures mentioned above are most favorable to the drawing capacity of certain brass alloys, other metals or alloys require different temperatures which can be ascertained in each case by a test. The kind of lubricant to be employed depends largely upon the working temperature.

The crank and lever arrangement for driving the grippers may be replaced by other means, such as a rack and pinion gear or a piston moving in a cylinder.

20 The machine may as well be employed for drawing work pieces other than ordinary tubes.

I claim:

25 1. In a machine for drawing thin-walled tubes from a blank in a cold state, the combination of a mandrel, a plurality of dies, and means for passing the dies separately in close succession over the mandrel.

30 2. In a machine for drawing thin-walled tubes from a blank in a cold state, the combination of a mandrel, a series of dies arranged side by side at one end of the mandrel and adapted collectively to effect the desired reduction of a blank supported by the mandrel, and means adapted to move said dies one by one in close succession over the mandrel.

35 3. In a machine for drawing thin-walled tubes from a blank in a cold state, the com-

bination of a mandrel, a plurality of dies, 40 and grippers arranged to reciprocate longitudinally of the mandrel and adapted to successively engage the several dies, whereby the dies will be separately moved, in close succession, over the mandrel. 45

4. In a machine for drawing thin-walled tubes from a blank in a cold state, the combination of a mandrel, a plurality of dies, means for separately engaging the dies and passing them in close succession over the 50 mandrel, and means for maintaining a blank on the mandrel at substantially uniform temperature throughout the drawing operation.

5. In a machine for drawing thin-walled 55 tubes from a blank in a cold state, the combination of a mandrel, a plurality of dies, means for passing the dies separately in close succession over the mandrel, and means for maintaining the mandrel, a blank thereon, and the operative die at the temperature at which the metal of the blank may be most readily drawn.

6. In a machine for drawing thin-walled 60 tubes from a blank in a cold state, the combination of a mandrel, a plurality of dies, means for passing the dies separately in close succession over the mandrel, and a trough containing a suitable liquid lubricant which surrounds the mandrel, a blank 65 thereon and the operative die. 70

In testimony whereof I affix my signature in presence of two witnesses.

HERMANN VON FORSTER.
